UNITED STATES PATENT OFFICE.

ERNEST L. DETRICK, OF CLEVELAND, OHIO.

TOOTH-BRUSH.

No. 851,501.

Specification of Letters Patent.

Patented April 23, 1907.

Application filed June 18, 1906. Serial No. 322,287.

To all whom it may concern:

Be it known that I, ERNEST L. DETRICK, a citizen of the United States, residing at Cleveland, in the county of Cuyahoga and State of Ohio, have invented certain new and useful Improvements in Tooth-Brushes; and I do declare the following to be a full, clear, and exact description of the invention, such as will enable others skilled in the art to which it appertains to make and use the same.

This invention relates to improvements in tooth brushes.

The object of the invention is to provide a simple and practical device of this character, in which the brush head will be given an oscillatory movement, so that the teeth may be thoroughly cleaned.

With the above and other objects in view, the invention consists of the novel features of construction, combination, and arrangement of devices hereinafter described and claimed.

In the accompanying drawings,—Figure 1 is a side elevation of the improved tooth brush; Fig. 2 is a top plan view of the same; Fig. 3 is a longitudinal sectional view; Figs. 4 and 5 are transverse sectional views, taken on the planes indicated by the lines 4—4 and 5—5 in Fig. 3; and Fig. 6 is a detail view showing the holder for the brush and a portion of the twisted shaft.

Referring to the drawings, 1 denotes a tubular shank, preferably of oval shape in cross-section, provided at one end with a handle 2, and at its other end with a transversely curved, longitudinal extension 3, which latter has its end bent inwardly at right angles and formed with a cone shaped bearing recess 4, a similar bearing recess 5 being provided upon the inner face of the opposite end of the shank, as shown in Fig. 3. These bearing recesses 4, 5, are adapted to receive the tapered or cone-shaped pivots 6, 7, of an oscillating element 8 comprising a twisted shaft 9 and a brush holder 10. The shaft 9 is disposed within the shank 1 and has the pivot 7 at one of its ends, and a cylindrical neck 11 at its other end. This neck 11 projects through and rotates in the end 12 of the neck, and has one end of the holder 10 formed upon or secured to it. This holder 10 which carries the pivot 6, is in the form of a plate having its ends curved inward toward each other, to receive the ends of a brush 14

and retain the latter removable therein. The shaft 9 is preferably in the form of a flat bar of steel or other metal, twisted at an angle of about sixty degrees, alternately, to the right and to the left, throughout its length, as clearly shown in Figs. 3 and 6. Slidably engaged with this shaft is the bifurcated inner end 15 of an operating finger-piece 16, which latter projects through and slides in a longitudinal slot 17, formed in the shank. 65 This finger-piece has upon its outer end a head or enlargement 18, and is steadied in its sliding movements by a curved plate 19, which is attached to it and which slides upon the outer face of the shank.

The operation and advantages of the invention will be readily seen. When the finger-piece 16 is moved longitudinally in the slot 17, it will be seen that its forked end 15 will cause the shaft 9 to be rotated or oscillated, first in one direction and then in the opposite direction, so that the brush head 14 will be given an oscillatory movement to cause its bristles to strike the teeth vertically or up and down and enter between them. It 70 will be noted that the device may also be used as an ordinary tooth brush for scrubbing or brushing the teeth horizontally or transversely. It will also be noted that the device is of simple, durable and comparatively inexpensive construction, and that it is easy to operate and very effective.

Various changes in the form, proportion, and the minor details of construction may be resorted to without departing from the principle or sacrificing any of the advantages of the invention, as defined by the appended claims.

Having thus described my invention, what I claim as new, and desire to secure by Letters-Patent, is,—

1. A tooth brush comprising a shank, an oscillating element, and a brush head removably attached to said element.
2. A tooth brush comprising a tubular shank formed with a longitudinal slot with an aperture at one end and a bearing recess in its other end, a handle at the latter end of said shank, a twisted shaft in said shank having one end engaged with said bearing recess and its opposite end projecting through said aperture, a brush holder upon said last-mentioned end of said shaft, a brush head in said holder, a pivot upon said holder, an extension upon said shank having a bearing recess 100
3. A tooth brush comprising a shank having a longitudinal slot with an aperture at one end and a bearing recess in its other end, a handle at the latter end of said shank, a twisted shaft in said shank having one end engaged with said bearing recess and its opposite end projecting through said aperture, a brush holder upon said last-mentioned end of said shaft, a brush head in said holder, a pivot upon said holder, an extension upon said shank having a bearing recess 105
4. A tooth brush comprising a shank having a longitudinal slot with an aperture at one end and a bearing recess in its other end, a handle at the latter end of said shank, a twisted shaft in said shank having one end engaged with said bearing recess and its opposite end projecting through said aperture, a brush holder upon said last-mentioned end of said shaft, a brush head in said holder, a pivot upon said holder, an extension upon said shank having a bearing recess 110

to receive the pivot upon said holder, a finger-piece projecting through and slideable in the slot in said shank and having a notched or slotted inner end to engage said twisted shaft, substantially as described.

3. A tooth brush comprising a shank, a shaft mounted therein and consisting of a flat bar twisted alternately in opposite directions at a brush head carried by said shaft, and a

slidably-operated element upon said shank to and engaged with said shaft.

In testimony whereof I have hereunto set my hand in presence of two subscribing witnesses.

ERNEST L. DETRICK.
